(57) **CLAIM**

The ornamental design for vehicle fender flares, as shown and described.

DESCRIPTION

FIG. 1 is a front top perspective view of a vehicle fender flare for the right side of a vehicle showing our new design.

FIG. 2 is a rear bottom perspective view thereof.

FIG. 3 is a right side elevational view thereof.

FIG. 4 is a left side elevational view thereof.

FIG. 5 is a front elevational view thereof.

FIG. 6 is a rear elevational view thereof.

FIG. 7 is a top elevational view thereof; and,

FIG. 8 is a bottom elevational view thereof.

For each view of the vechile fender flare for the right side of a vehicle, a vehicle fender flare for the left side of a vehicle is a mirror image thereof and the mirror images are claimed.
